SURFACE ACTIVE AGENT AND THE PROCESS
OF TREATING FIBROUS MATERIALS
THEREWITHHillary Robinette, Terre Haute, Ind., assignor to
Commercial Solvents Corporation, Terre Haute,
Ind., a corporation of MarylandNo Drawing. Application November 15, 1941,
Serial No. 419,318

7 Claims. (Cl. 252—355)

My invention relates to new and useful surface active substances, and more particularly it is concerned with a series of compounds, the general type of which has never been, to my knowledge, recognized as possessing wetting and penetrating properties, as well as other surface active characteristics. These compounds may be represented by the following structural formula:

wherein R¹ represents an alkyl group containing at least five carbon atoms, and R² is an alkyl group.

Specific examples of the substituted 1,3-dioxanes which belong to the class represented by the above generic formula are 5-amino-5-nethyl-2-(3-hyptyl)-1,3-dioxane, 5-amino-5-thyl-2-(1-ethyl-1-pentenyl)-1,3-dioxane, 5-amino-5-propyl-2-(1-ethyl-1-pentenyl)-1,3-dioxane, 5-amino-5-ethyl-2-(3-heptyl)-1,3-dioxane, 5-amino-5-propyl-2-(3-heptyl)-1,3-dioxane, 5-amino-5-ethyl-2-hendecyl-1,3-dioxane, 5-amino-5-methyl-2-hendecyl-1,3-dioxane, 5-amino-5-methyl-2-(1-ethyl-1-pentenyl)-1,3-dioxane, 5-amino-5-propyl-2-(1-ethyl-1-pentenyl)-1,3-dioxane, and the like.

In numerous industries there exists a need for certain types of chemical compounds ordinarily employed in small quantities, to secure an effect which is principally the result of a wetting action, such as the effect obtained by the presence of a surface active agent at a water-oil interface. For example, in the textile and leather-treating industries there are many situations where wetting or detergent action is highly desirable. As a result, many different agents have been proposed to reduce surface tension and promote wetting. The materials previously employed, however, although satisfactory in some respects, have not met with unqualified success in all cases.

The ordinary soaps, although their surface active properties have long been recognized, are efficient in many respects when employed in the field of detergent and wetting agents. For example, although soaps act efficiently as detergents in weakly alkaline solutions, they are of no value for this purpose in acid solutions, since under such circumstances the free fatty acid,

which is insoluble in water, is liberated. In strongly alkaline solutions, on the other hand, ordinary soaps become insoluble and are salted out of solution. In addition, in the presence of solutions containing calcium or magnesium salts such as ordinary hard water, the fatty acid present in the soap is precipitated as a calcium or magnesium soap, such soaps being insoluble sticky materials which, rather than having any detergent action, are regarded as undesirable impurities in solutions employed in the textile and related industries.

In an effort to furnish materials to such industries free from the undesirable properties of ordinary soaps, there have been developed as detergent and wetting agents products obtained by the sulfonation of certain fatty acids occurring in oils and fats. Such fatty acids are characterized by containing unsaturated linkages and/or hydroxyl groups in the molecule. On sulfonating such acids, products are obtained which contain sulfuric acid ester groups in the molecule, and of course carboxylic acid groups are attached to the terminal carbon atom. The products, however, in general possess weaker wetting and detergent properties than soaps. Such products are also relatively unstable, and are capable of being decomposed by hydrolysis.

Other proposed wetting agents comprise the semi- and completely-esterified products resulting from the esterification of a higher alcohol with an unsaturated polybasic acid. After the unsaturated esterified acid is produced, it is converted into a more soluble form, ordinarily by treatment with sodium bisulfite to yield the corresponding sulfo derivative of the esterified polybasic acid. While such materials have met with a considerable degree of success in various industries where the need for surface-active materials exists, they are not without defects. Obviously, surface-active agents of this type are not stable to alkali, and in some instances, especially in the textile field, much difficulty has been experienced with the tendency of the textile-treating baths containing such materials, to foam.

I have now discovered that the aminodioxanes included by the above generic formula, when employed with a suitable solubilizing agent, impart valuable surface-active properties to solutions thereof. Such wetting agents have been found to be particularly useful under conditions where previous wetting and penetrating agents, especially of the type mentioned above, are of little or no value. For example, the wetting

agents of the present invention are not decomposed either by hard water, or solutions containing appreciable quantities of alkali. These new wetting agents possess the further advantage in that aqueous solutions thereof do not foam.

In general, the quantity of aminodioxanes that may be employed, will be found to vary with the type of wetting operation under consideration, as well as with the material to be wetted. For the greater majority of uses, however, I have found that the aminodioxanes are most advantageously employed in amounts of from about .09 to 2.0 per cent by weight of the treating bath. The quantity of solubilizing material to be utilized in preparing the wetting agents of the present invention, will also be found to differ, depending of course upon the type of solubilizing agent employed and the character of the substance which is to be treated. Generally, I have found it suitable to employ the solubilizing agent in amounts varying from approximately 10 to 35 per cent, based upon the weight of the aminodioxane used. As examples of suitable solubilizing materials which may be employed in preparing the wetting agents of the present invention, there may be mentioned sulfonated castor oil, sulfonated petroleum oils, sulfonated alkyl aromatic compounds, sulfated esters, sulfated ether alcohols, sulfonated alkyl diphenyls, and the like.

The wetting and penetrating powers of certain of the wetting agents covered by the present invention have been compared with some of the commercially-available agents, the results of the tests performed appearing in the table below. The wetting properties of the various agents tested were measured by the method of Draves and Clarkson (Am. Assoc. Textile Colorists' and Chemists' Year Book, vol. 17, pp. 216-222 (1940)) which determines the sinking or wetting-out time required for a five-gram skein of unboiled two-ply yarn in varying concentrations of aqueous solutions of wetting agents. These tests were performed at a temperature of approximately 30° C.

Aminodioxanes of the type mentioned above were solubilized by blending 120 parts of 14.5 per cent aqueous sulfonated castor oil with 50 parts of the aminodioxane. The sinking times of aqueous solutions containing three grams per liter of the blend of certain of the aminodioxanes, are shown in the following table:

Table I

Wetting agent	Wetting-out time
5-amino-5-methyl-2-(3-heptyl)-1,3-dioxane.	Skein sinks instantly.
5-amino-5-ethyl-2-(1-ethyl-1-pentenyl)-1,3-dioxane.	36 seconds.
5-amino-5-ethyl-2-(3-heptyl)-1,3-dioxane.	Skein sinks instantly.
5-amino-5-ethyl-2-hendecyl-1,3-dioxane.	60 seconds.

The examples which follow illustrate typical wetting agents containing aminodioxanes of the above type, and also demonstrate the ability of said aminodioxanes to improve the wetting characteristics of solutions containing commercially-available wetting agents.

Example I

A solution consisting of 50 parts of 5-amino-5-ethyl-2-(3-heptyl)-1,3-dioxane in 35 parts of 50 per cent sulfonated castor oil and 85 parts of distilled water, was prepared. The wetting

power of the resulting solution was then measured at 30° C. by the method of Draves and Clarkson, the following data being obtained:

	Grams per liter	Wetting-out time
5	3.5	Instantaneous.
	3	Do.
10	2	14 seconds.
	1.5	21 seconds.
	1	68 seconds.

Example II

15 A solution consisting of 20 parts of Triton W-30 (a sulfated ether alcohol) and 10 parts of 5-amino-5-ethyl-2-(3-heptyl)-1,3-dioxane was found to have a wetting time of 21 seconds in concentrations of 1.5 grams per liter at 25° C., according to the Draves' test. The wetting time 20 is instantaneous at a concentration of 3 grams per liter in distilled water. In water of 18 grains hardness, the solution exhibited a wetting time of 32 seconds at a concentration of 1.5 grams per liter, and 23 seconds at 3 grams per liter. 25 Triton W-30 alone possessed a wetting time of 87 seconds at 1.5 grams per liter, and 37 seconds at a concentration of 3 grams per liter.

Example III

30 The wetting power of a solution consisting of 10 parts of Santomerse No. 1 (a sulfonated alkyl di-phenyl), 10 parts of 5-amino-5-ethyl-2-(3-heptyl)-1,3-dioxane, 40 parts of 95 percent alcohol, and 80 parts of water was measured, in accordance with the method of Draves and Clarkson, the following results being obtained:

	Grams per liter	Wetting-out time
40	6	12 seconds.
	5	15 seconds.
	4	30 seconds.
	3	60 seconds.

45 Under similar conditions the wetting power of solutions containing only Santomerse No. 1, in varying concentrations, were found to have the following wetting-out activity when measured 50 according to the method of Draves and Clarkson:

	Grams per liter	Wetting-out time
55	5	6.2 seconds.
	2.5	12.9 seconds.
	1.25	24 seconds.
	.6	Over 3 minutes.

60 It will be apparent from the above data that the addition of 5-amino-5-ethyl-2-(3-heptyl)-1,3-dioxane to a formula using Santomerse No. 1 gives a much faster wetting time than aqueous solutions containing only Santomerse No. 1. For example, 6 grams per liter of the wetting agent containing both 5-amino-5-ethyl-2-(3-heptyl)-1,3-dioxane and Santomerse No. 1 is equivalent to .84 gram per liter of Santomerse No. 1. The former wetting agent, in concentrations of 6 grams per liter, gives a solution possessing a wetting time of 12 seconds, whereas a solution containing .84 gram per liter of Santomerse No. 1 possesses a wetting time which is appreciably in excess of 34 seconds.

65 The aminodioxanes of the present invention 70 may be prepared in accordance with any of sev-

eral suitable procedures. I prefer, however, to produce such materials by means of the process described in U. S. Patent No. 2,247,256 granted June 24, 1941, to Murray Senkus. According to this procedure, the corresponding nitrodioxane is subjected to high-pressure hydrogenation in the presence of a nickel catalyst and a suitable solvent, such as methanol, at a temperature in the neighborhood of 25-30° C. The starting materials in this process are conveniently prepared by condensing a suitable poly-hydroxy nitro compound with an aliphatic aldehyde, such as hexanal, heptanal, heptaldehyde, 2-ethyl-hexanal, dodecanal, and the like. This condensation reaction is carried out by heating the polyhydroxy nitro compound in the presence of the desired aldehyde and a small quantity of an acid catalyst, and if desired, in the presence of an organic liquid, such as benzene or toluene, which is capable of removing the water produced during the reaction in the form of a constant boiling mixture.

In regard to the single compounds covered by certain of the appended claims, these products, i. e., 5-amino-5-methyl-2-(3-heptyl)-1,3-dioxane, and 5-amino-5-ethyl-2-(3-heptyl)-1,3-dioxane, may be prepared by first synthesizing the corresponding nitrodioxane, which in the case of the former compound involves the condensation of 1 mole of 2-methyl-2-nitro-1,3-propanediol with 1 mole of 2-ethylhexanal, while the latter amino dioxane requires the condensation of 1 mole of 2-ethyl-2-nitro-1,3-propanediol with 1 mole of 2-ethyl-hexanal. Both condensation reactions require the presence of a small quantity of a mineral acid, such as sulfuric acid to serve as a catalyst. The respective nitro dioxanes, prepared in this manner, are then dissolved in a suitable solvent such as methanol and subjected to the action of hydrogen at a temperature of 25-30° C., and at a pressure of 2000 pounds per square inch in the presence of Raney nickel, to produce the corresponding amino dioxane.

It is understood that applicant does not claim the amino dioxanes per se described and referred to herein but instead claims merely the new and novel use of said compounds which is disclosed herein.

Wetting agents of the type contemplated by the present invention are especially suited for use in the preparation of printing pastes and sizing mixtures. They may also be used as penetrants in flax-retting baths. These products serve as useful wetting, cleansing, and penetrating agents in bleaching liquors, such as those used in kier boiling of cotton goods, and may be added to the lye liquors used for mercerizing cotton goods. They can also be used to assist in twist setting of yarn and in processes of stripping colors. Such compounds also find use as assistants in processes of stripping dyes from dyed textile material.

A second class of uses of these new surface-active agents constitutes their use as assistants in the application of dyestuffs. They may be employed as dye-leveling agents due to their wetting and penetrating powers in neutral or alkaline dyeing baths, and are capable of facilitating dyeing with developed dyes, the dyeing of acetate fibers with insoluble dyes, the dyeing of animal fibers with vat dyes, the dyeing of various synthetic fibers, and the dyeing of leather.

It will readily be seen from the foregoing description that by means of the present invention, a large group of new surface-active substances

has been made available, and that such agents are adapted for use in numerous industrial processes which require surface-active materials. It will also be apparent to those skilled in the art that many widely different embodiments of the present invention exist, and that such embodiments may be utilized without departing from the scope of said invention.

My invention now having been described, what

10 I claim is:

1. A bath for the wet treatment of organic fibrous materials to change the surface active properties thereof, comprising an added solubilizing compound of the sulfur-containing type 15 and an aminodioxane having the formula:

20 25 wherein R¹ represents an alkyl group containing at least 5 carbon atoms, and R² is an alkyl group.

2. An aqueous bath for the wet treatment of organic fibrous materials to change the surface 30 active properties thereof, comprising an added solubilizing compound of the sulfur-containing type and an amino-dioxane having the formula:

35 40 in which R¹ represents an alkyl group containing at least 5 carbon atoms, and R² is an alkyl group.

45 3. An aqueous bath for the wet treatment of organic fibrous materials to change the surface active properties thereof, comprising an added solubilizing compound of the sulfur-containing 50 type and from about 0.09 to 2 per cent by weight of the bath of an aminodioxane having the formula:

55 60 wherein R¹ represents an alkyl group containing at least 5 carbon atoms, and R² is an alkyl group.

65 4. An aqueous bath for the wet treatment of organic fibrous materials to change the surface active properties thereof, comprising an added solubilizing compound of the sulfur-containing type and 5-amino-5-ethyl-2-(3-heptyl)-1,3-dioxane.

70 75 5. In the process for the wet treatment of organic fibrous materials in an aqueous bath to improve the surface active properties thereof, the improvement which comprises incorporating in the bath in an amount to change its surface active properties a composition consisting of an

added solubilizing agent of the sulfur-containing type and an aminodioxane of the formula:

wherein R¹ represents an alkyl group having at least 5 carbon atoms, and R² is an alkyl group.

6. In the process for the wet treatment of organic fibrous materials in an aqueous bath to improve the surface active properties thereof, the improvement which comprises incorporating in

the bath in an amount to change its surface active properties a composition consisting of an added solubilizing agent of the sulfur-containing type and 5-amino-5-ethyl-2-(3-heptyl)-1,3-dioxane.

5. 7. In the process for the wet treatment of organic fibrous materials in an aqueous bath to improve the surface active properties thereof, the improvement which comprises incorporating in
10 the bath in an amount to change its surface active properties a composition consisting of an added solubilizing agent of the sulfur-containing type and 5-amino-5-methyl-2-(3-heptyl)-1,3-dioxane.

15

HILLARY ROBINETTE.
